UNITED STATES PATENT OFFICE
Grover S. Moore, Jr., Houston, Tex.
Application May 15, 1944, Serial No. 535,674
1 Claims. (Cl. 254—193)

The present invention relates to new and useful improvements in snatch blocks of the type comprising a side plate which may be swung to open position to facilitate the insertion or removal of the rope or cable.

An important object of the invention is to provide a snatch block of the aforementioned character comprising novel latching means whereby the swingable side plate may be opened only when the supporting hook is in inoperative position.

Another important object of the invention is to provide a snatch block comprising a latching means which will prevent spreading of the side plates in the event of failure of the sheave pin.

Other objects of the invention are to provide an improved snatch block of the character set forth which will be comparatively simple in construction, strong, durable, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a snatch block constructed in accordance with the present invention with a portion broken away to reveal the latching means.

Figure 2 is a view in front elevation of the device.

Figure 3 is a side elevational view, showing the snatch block open.

Figure 4 is a view in side elevation of the crosshead, showing a portion of the supporting hook mounted thereon.

Figure 5 is a detail view in transverse section, taken substantially on the line 5—5 of Figure 4.

Figure 6 is a fragmentary view in section, taken substantially on the line 6—6 of Figure 3.

Figure 7 is an elevational view of the swingable plate, looking at the inner side thereof.

Referring now to the drawings in detail, it will be seen that the embodiment of the invention which has been illustrated comprises a pair of substantially oval side plates 1 and 2 of suitable metal. Mounted on the plate 1 is a bolt 3 on which the plate 2 is swingable. A sheave 4 is journaled on the bolt 3 between the plates 1 and 2.

The upper portion of the plate 1 has formed therein an opening 5 in which a crosshead 6

is journaled. As illustrated to advantage in Figures 4 and 5 of the drawings, the crosshead 6 includes a block 7 in which a supporting hook 8 is swivably mounted. Projecting in opposite directions from the block 7 are trunnions 9 and 10. The trunnion 9, which is circular in transverse section, is journaled in the opening 5 in the plate 1 and has formed thereon a retaining head 11. The trunnion 10 is of an elongated, substantially segmental transverse section, said trunnion having flat opposite side portions 12. A circular head 13 is provided on the trunnion 10.

Extending into the upper portion of the plate 2 from an edge 14 thereof is a keyhole slot 15 for the reception of the trunnion 10. Fixed as by welding on the upper portion of the plate 2 are intermediate and outer plates 16 and 17, respectively. Extending into the plate 16 is a comparatively large slot 18 with which the keyhole slot 15 registers. The slot 18 accommodates the head 13 on the trunnion 10. The plate 17 constitutes a cover for the slots 15 and 18.

It is thought that the operation of the device will be readily apparent from a consideration of the foregoing. Briefly, with the plate 2 in closed position, as seen in Figure 1 of the drawings, the trunnion 10 is engaged in the keyhole slot 15 and the head 13 is engaged in the slot 18. With the supporting hook 8 in vertical or operative position, the transversely elongated trunnion 10 is journaled in the enlarged, circular inner end portion 19 of the keyhole slot 15 at an angle to the relatively narrow neck or throat portion of said keyhole slot. Thus, the trunnion 10 cannot enter the narrow portion of the keyhole slot 15 and it will accordingly be seen that the swingable side plate 2 is positively locked in closed position. The circular head 13 is journaled in the rounded inner end portion 20 of the slot 18 and said head functions as a bearing for assisting in supporting the plate 2. Further, the head 13, being engaged with the outer side of the plate 2 around the portion 19 of the keyhole slot 15, prevents spreading of the plates 1 and 2 should the sheave pin 3 break. An opening 21 in the plate 2 accommodates the pin 3. To open the plate 2, as seen in Figure 3 of the drawings, the hook 8 is swung downwardly to inoperative position. In this manner the transversely elongated trunnion 10 is positioned to enter the relatively narrow neck or throat portion of the keyhole slot 15 and the plate 2 may be readily swung open on the pin 3.

It is believed that the many advantages of a snatch block constructed in accordance with the

present invention will be readily understood, and although a preferred embodiment of the device is as illustrated and described, it is to be understood that changes in the details of construction may be resorted to which will fall within the scope of the invention as claimed.

What is claimed is:

A snatch block of the character described comprising a plate, a sheave pin mounted on said plate, a sheave journaled on said pin, a cross-head journaled on said plate, a supporting hook mounted on said crosshead, a plate mounted for swinging movement on the pin, intermediate and outer plates mounted on the swingable plate, the intermediate plate having a relatively wide slot extending from an edge thereof, the swingable plate having a keyhole slot in registry with the

first-named slot and extending into said swingable plate from an edge thereof, the larger diameter of said keyhole slot being less than the width of said first-mentioned slot, the crosshead comprising a trunnion of transversely elongated, substantially segmental cross section having flat opposite side portions, said trunnion being engageable in the keyhole slot and rotatable in the inner end portion thereof, said trunnion constituting means for supporting the swingable plate and for releasably securing same against swinging movement on the pin, and a circular head on the trunnion engageable in and rotatable on the walls of the first-named slot, said head further being engaged with the outer face of the swingable plate.
